UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

PULP-SCREEN.

1,185,795.

Specification of Letters Patent. Patented June 6, 1916.

Application filed January 14, 1915. Serial No. 2,249.

To all whom it may concern:

Be it known that I, ANTON J. HAUG, a citizen of the United States, and a resident of Nashua, county of Hillsboro, and State 5 of New Hampshire, (whose post-office address is care of Improved Paper Machinery Company, Nashua, New Hampshire,) have invented an Improvement in Pulp-Screens, of which the following description, in connection with the accompanying drawings, is 10 a specification, like characters on the drawings representing like parts.

This invention relates to pulp screens or strainers and more particularly, though not 15 exclusively, to machines of the type wherein the stock is delivered to the interior of the screen and forced against the same by means of an impeller, the fine fibers being forced through the screen and the coarser 20 particles being discharged from within at the end thereof.

For purposes of illustration I have herein shown the invention embodied in a screen of the horizontal-shaft type having a substantially cylindrical straining drum and a 25 centrifugal impeller embodying a series of impeller blades adapted to revolve at a sufficiently high speed to throw or beat the pulp against the inside of the straining drum.

The invention relates more particularly, though not exclusively, to improved means for feeding and distributing the pulp to the impeller blades; to the efficient distribution of the pulp with reference to the rate 30 of supply; to the simple and effective application of shower water to the stock while being screened; to the reduction of power required for driving the machine, and to other features designed to increase the effectiveness of the screening action and the capacity of the machine.

The invention will be best understood by reference to the following description when taken in connection with the accompanying 45 illustration of one specific embodiment thereof, while its scope will be more particularly pointed out in the appended claims.

In the drawings: Figure 1 is a central, longitudinal section in elevation showing a 50 pulp screen embodying one form of the invention; Fig. 2 is a partial section in end elevation of the machine shown in Fig. 1,

looking from the left; Fig. 3 is a plan of a pair or set of impeller blades of the type shown in the machine of Fig. 1, but shown on a larger scale; Fig. 4 is a front elevation of the same blades shown in Fig. 3; Fig. 5 is a section on the line 5—5 in Fig. 4; and Fig. 6 is a section on the line 6—6 in Fig. 4.

Referring to the illustrative embodiment 60 of the invention and more particularly to Fig. 1, the machine there shown is provided with end frame members or castings 1 and 2 resting upon the feet 3 and 4 and providing bearings 5 and 6 for the impeller shaft 65

7. The latter is driven by any suitable means, as, for example, by the belt-driven pulley 8 shown at the left in Fig. 1. The end castings hold fixedly supported between them a substantially cylindrical casing 9 70 within which there is provided a screen 10 of a smaller diameter than the casing so that there is provided outside of the screen and within the casing an annular screened pulp-receiving chamber 11, the bottom of which 75 is provided with a discharge conduit 12 (Fig. 2) from which the screened pulp is discharged to any suitable receptacle. The screen may be of any suitable shape, but is preferably cylindrical and may be of any 80 usual construction to provide usual or suitable screening openings. The opposite ends of the annular screened pulp-receiving chamber are closed by annular end plates 13 and 14, respectively, through the annular 85 openings of which are discharged from within the screen the coarser particles which cannot pass through the screen. The end plates 13 and 14 are provided with inwardly turned flanges 15 and 16, respectively, which 90 serve as bearing supports for the screen 10 when, as in the case of the illustrative embodiment of the invention, the screen is made rotatable. The screen is secured at opposite ends directly to the annular supporting members 17 and 18, the latter in turn being secured to the bearing rings 19 and 20, respectively, whereby the screen has journaled support upon the flanges 15 and 16 95 of the end plates. To prevent the un-

screened particles from being forced through this joint into the screened pulp-receiving chamber or the screened particles from being forced into the waste outlet, the screen sup-

ports 17 and 18 are provided with inner flanges or discharge aprons 21 and 22. These extend from the annular screen supports outwardly over and beyond the end plates so that the passage of the coarser waste into the waste outlet is insured. To force the stock against the interior of the screen the impeller shaft 7 is provided with a centrally arranged hub 23 keyed to the shaft and carrying the centrally arranged disk 24 to which are secured impelled blades extending longitudinally of the screen and adapted to rotate in close coöperative relation to the interior of the screen. These blades extend longitudinally of the screen and in the illustrative embodiment of the invention have a slight rearward inclination from the center of the screen outwardly with relation to the direction of rotation so that they serve not only to force the pulp against the screen but to feed the coarser, unscreened particles toward the sliver or waste outlet.

To secure certain objects of the invention (though not essential as to other features) in the illustrative embodiment the impeller blades consist of two sets, the blades 30 of one set being substantially alike and the blades 31 of the other set being also substantially alike, but differing somewhat from the blades 30 and arranged in alternation with reference to the latter. For convenience in manufacture the blades are constructed in pairs as indicated in Figs. 3 to 6, inclusive, a blade 30 and a blade 31 being cast or formed in one unit. These are joined at their outer ends by the rib or connecting piece 32 and at their inner ends by the connecting plate 33, the latter being utilized to bolt or otherwise secure the unit consisting of the two blades directly to one side of the supporting disk 24 on the impeller shaft. One unit or pair of blades when thus fastened to the side of the driving disk 24 is arranged to lie in registration with a similar set of blades secured to the opposite side of the disk and extending in the opposite direction. The adjoining edges of the two sets of blades are inwardly curved at their upper, inner corners 34 and 35 so that they project over the edge of the disk and come into substantial contact. The two sets of blades thereby constitute in effect two continuous blades extending lengthwise the screen but inclined rearwardly with reference to the direction of rotation from the central support to the ends of the screen as indicated in Fig. 3, so that the stock fed to the impellers as hereinafter described is gradually worked toward the end of the screen. The two blades 30 and 31 while having substantially the same general longitudinal configuration as viewed in Fig. 1, that is, the same projection, are substantially different in their cross sectional outline as indicated in Figs. 2, 5 and 6. I have herein provided means (herein-

after described) for so feeding the pulp to the impellers that it enters in a substantial amount only at the front of the blade 31 and at the rear of the blade 30, that is to say, to the space between the blades 30 and 31 constituting the unit shown in Figs. 3 and 4. By this provision the head or feeding pressure of the pulp against the back of the preceding blade 30 may be availed of to assist the rotation of the impeller, while the front of the succeeding blade 31 may be used to impel or direct the pulp and may be shaped more effectively for that purpose. This further provides for feeding the pulp intermittently or in batches to the impeller so that each batch so fed to the screen is beaten against the screen not only by the edge of the impeller blade which feeds it, but also by the edge of the next succeeding pulp-impelled blade 30 which strikes it and gives it a second impact before any further pulp can reach that portion of the screen. To this end the back face of the pulp-impelled blade 30 is best shaped having reference to the speed of rotation of the blades and the velocity and pulp flow so that the impact of the pulp in passing outwardly through the pulp-receiving space lends material assistance to the rotation of the impeller. By increasing the number of blades to a point where the velocity of pulp flow is greater than the speed of the blades necessary to press the pulp against the inside of the screening drum, sufficient rotative effect can be absorbed from the flow of the pulp to materially decrease the power required for driving the impeller.

The pulp impelling blade 31 as viewed in cross section after starting at 36 in a direction substantially radial sweeps back into a portion 37 having a low pitch or slope with relation to a tangential line. The pitch of the blade surface then increases at first slowly and then rapidly toward the edge of the blade, the outer edge at 38 having a relatively sharp pitch. The result is that after the stock has entered between the blades it moves along the impelling blade 31 at first slowly along the middle or low pitched portion 37 and then with increasing velocity until it is thrown from the high pitched portion 38 against the screen with considerable force, the edge of the blade tending to beat the pulp through the screen as it passes over the same. The gradual acceleration given to the movement of the pulp as it passes along the impeller blade diminishes the shock which is imparted to the impeller. The inclination of the impeller blade provides a wide blade in a small, compact, radial space over which the stock may be spread out and thoroughly distributed.

The stock is preferably fed from within and radially outward between the blades by

any suitable means, but herein there is employed one or more stock feeding passages which enter through the annular plates 13 and at one end of the screen and terminate 5 in one or more discharge orifices located within the blades. In the illustrated form of screen the stock is fed through both open ends of the machine toward the middle thereof, the unscreened particles being fed 10 back by the blades away from the center toward the opposite ends of the casing where they are discharged into a waste chamber 39 at the end of the screen opening into the waste or sliver outlet 39^x.

15 The two opposite sets of feeding passages and orifices are substantially similar in construction. Any number of feeding passages may be provided at each end of the drum, but herein I have shown two such passages 20 comprising an inner, annular passage 40 formed by the inner, fixed walls 41 and the outer, fixed walls 42, and a second exterior, annular feed passage 43 formed by the fixed wall 42 and the fixed enveloping but separated wall 44, the latter separating the passage 43 from the waste outlet 39. Both feed 25 passages communicate with a stock supply chamber 45 formed in the end frame or casing 1 or 2, said chambers communicating 30 with a common supply chamber 46 at the top of the machine, the latter being connected with any suitable source of pulp supply, preferably under pressure.

While a discharge orifice or orifices of any 35 suitable shape or number may be provided, herein I have shown a discharge orifice for both passages annular in form so that the discharge of the pulp is in a general, radial direction and symmetrical for the entire 40 distance around the impeller. The orifice for the passage 40 consists of an annular opening 47 formed between the walls 41 and 42, while the discharge orifice for the 45 passage 43 consists of an annular opening 48 between the wall 42 and the wall 44.

The two feeding passages 40 and 43 are utilized in conjunction with a pulp distributing device which is designed automatically to regulate the feed of the pulp so that the 50 latter will be subjected to substantially the same extent of screening, irrespective of the variations in the rate of supply.

For most efficient screening the pulp should be fed to the screen at a constant rate 55 of supply if the distance through which the pulp travels over the screen is unchanged. If the rate of supply decreases the screening becomes too severe, while if it increases beyond the capacity of the machine, good 60 stock passes to the waste. Under ordinary working conditions it is difficult to maintain a constant rate of pulp supply, for the latter is constantly undergoing variations. I have therefore arranged in each supply 65 chamber 45 means for equalizing the screen-

ing action under the condition of variable supply by distributing the pulp to different points lengthwise the screen drum as the supply varies. For this purpose there is provided an adjustable dam or weir plate 50 70 mounted on the partition 51 between the respective inlets for the feed passages 40 and 43, said plate being of such a height that when the rate of supply is under the normal the pulp will only enter the feed passage 43. 75 The entire pulp supply is then discharged through the feed orifice 48, the capacity of the machine being such that the pulp in traveling from the orifice 48 outwardly over the screen to the discharging outlet is subjected to a suitable and sufficient screening action. If the rate of supply increases the pulp will flow over the adjustable weir plate 50 and the surplus, or that entering the supply passage 40, will flow to the supply passage 50 and be discharged through the orifice 80 85 47. This orifice is so located that the pulp discharged therefrom will be subject to a suitable and sufficient screening action in its travel from the orifice 47 to the region of the orifice 48. By this means the variations in pulp supply may be automatically taken care of and the screening action be maintained constant irrespective of variations in supply. 90 95

While I have herein shown two differently positioned discharge orifices and their respective supply passages, it will be evident that as many separate channels and successive weir plates as is desirable and practicable may be utilized and the same may be constructed in widely different forms and shapes from that herein shown. When the weir plates are once set for a certain condition they automatically take care of the distribution, but they may be adjustable as indicated in Fig. 1, whereby the whole of the pulp may be deflected to any one of the feeding orifices shown. 100 105

In order to provide that the stock fed 110 from the orifices 47 or 48 shall enter in a substantial amount only into the pulp-receiving spaces between the back of the pulp-impelled blade 30 and the pulp-impelling blade 31 and prevent its entrance to any substantial 115 extent into the intermediate spaces, suitable means are provided, herein consisting of obstruction members carried by the blades, for obstructing the free passage of the pulp from the annular outlets to the intermediate spaces. These may be of any suitable form, but herein they consist each of a plate 51 (Figs. 1 and 2) which extends between the back of the impelling blade 31 and the front 120 of the impelled blade 30 directly overlying and in close approximation to the annular orifice 47 so that the pulp cannot escape in any substantial amount from the latter into the intermediate or non-pulp-receiving 125 spaces between the blades. Similar obstruc- 130

tion plates 52 are carried between the blades 31 and 30 to obstruct and prevent the passage of pulp from the orifice 48 to the non-pulp-receiving spaces. The plates 51 are of 5 a suitable shape to practically cover the orifice 47 and are carried each by the brackets 53 bolted to the back of an impelling blade 31. Similarly the plates 52 are supported by brackets 54 bolted each to the back of an 10 impeller blade 31 at a position directly opposite the annular orifice 48.

The described feeding arrangement provides for the intermittent feeding of the stock between the impeller so that each 15 un-screened portion of the batch fed to the screen receives the impact not only of the impeller blade 31 which discharges it against the screen, but also the impact of the next adjacent pulp-impelled blade 30 before 20 any further material is discharged against a screen from the next succeeding pulp-receiving space. In the disclosed embodiment of the invention there is also provided means for supplying shower water or other liquid 25 and distributing it to the most effective points upon the screen. To supply the shower water supply pipes 60 are provided, one entering each end of the drum, these pipes adapted to discharge water each 30 through the open end of a conical-shaped water distributing receptacle 61 bolted or otherwise secured to the side of the rotating drum 24. The water on being discharged from the stationary pipe 60 to the 35 rotating chamber is thrown by centrifugal force to that portion of the chamber or receptacle of greatest diameter, which, herein, is closely adjacent the drum 24, but which might be located at other points lengthwise 40 of the blades as desired. At its point of greatest diameter each receptacle 61 is provided with water discharge orifices 62 through which the water is discharged radially outward between the blades and thereby distributed to the pulp being screened. This 45 method of supplying shower water avoids the necessity of using stuffing boxes.

To distribute the shower water evenly along the blades means are provided such as 50 the deflecting plates 63 to receive the shower water as it is thrown out from the chamber 61 and carry it lengthwise the blade to the desired point. Each deflector is in the form of a shelf attached to or formed integral 55 with the front of the blade 30 forming a trough to guide the water lengthwise the blade until the end of the plate is reached, at which point it is allowed to discharge radially outward upon the pulp. By making 60 one set of deflecting plates terminate close to the disk 24 as indicated at the top of Fig. 1, another set extend a little farther, as indicated at the bottom of Fig. 1, and successive sets extend for varying distances 65 toward the outer end of the blades, the wa-

ter may be directed from one blade close to the center and from the next blade a greater distance from the center and so on, effecting thereby for a single rotation of the impeller an even distribution of the shower water 70 lengthwise the screen.

While the water might be admitted between each successive blade indiscriminately and commingled with the pulp as it is impelled outwardly through the 75 pulp-receiving spaces, herein the discharge orifices 62 from the water chamber 61 are placed out of registration with the spaces in advance of the pulp-receiving blades and in registration with the intermediate spaces. 80 The water is therefore fed only to the intermediate spaces and applied only in substantial amount to the pulp which is undergoing screening action after delivery by the impeller blades to the screen. The impeller 85 therefore consists of a succession of blades forming intervening compartments consisting of pulp-distributing compartments and intermediate and alternating liquid distributing compartments. 90

While the screen 10' might be held fixed, I have herein shown the same mounted for rotation upon the annular supporting members 17 and 18 which are rotatable upon the bearing flanges 15 and 16, as heretofore described. The screen might be rotated in either direction by power, but herein I permit the frictional contact or impact of the pulp itself against the interior of the screen by the impeller blades to rotate the screen, 100 and control its rotation by means of a suitable braking device. For this purpose the bearing rings 19 and 20 are each provided with gear teeth 65 which mesh with pinions 66 mounted upon a shaft 67 extending 105 parallel with the screen. At its outer end (see Figs. 1 and 2) the shaft 67 is provided with the brake drum 68 engaged by the brake shoes 69, the latter secured respectively to the pivoted levers 70 so that they 110 can be drawn together and frictionally applied to the brake drum. To control the brake the upper ends of the levers are jointed to blocks 71 which have threaded engagement with the right and left threads of a 115 screw shaft 72, the latter journaled in the brake casing 73 and having the hand wheel 74 by which the brake may be released or applied to a varying extent. A hand wheel 80 (see Fig. 1) is keyed to the end of the 120 shaft 67 outside of the brake casing 73, so that the shaft 67 and the screen may be turned by hand when required. The hub of the hand wheel 80 is provided with a pin 81 adapted to enter a hole in the side of the 125 brake casing so as to lock the hand wheel and the shaft thereto and prevent the turning movement of the screen as required, or the pin may be withdrawn to permit the free rotation of the screen. 130

By adjusting the brake through the hand wheel 74 the speed of the screen may be controlled and retarded to a sufficient point to give the required screening action. The impact of the cleansing water alone is sufficient to rotate the screen and, in fact, the pressure of the air through the pulp feed spout when no pulp is being fed is also sufficient to rotate the screen. The rotation of the screen may be employed to insure thorough cleansing of the screen when cleansing water alone is supplied thereto without the feeding of pulp. Through a rotation of the screen a ready inspection of the apparatus may be had by merely taking off one of the plates from the inclosing casing.

While I have herein shown and described for purposes of illustration one specific form of the invention, it is to be understood that the same is not limited to specific details of construction herein shown or the relative arrangement or relation of parts, but that extensive deviations may be made therefrom without departing from the spirit of the invention.

Claims:

1. In a machine of the class described, the combination with a casing of a screen drum, blades rotatably mounted within and to cooperate with the drum, a support on which the blades are mounted, means for rotating the blade support, said blades being arranged in pairs and each pair consisting of a preceding pulp-impelled blade and a succeeding pulp-impelling blade, the pulp-impelled blade being inclined to impart a blade-rotating movement to the blade support under the feeding pressure of the pulp, and means to supply pulp to the back of the pulp-impelled blade only.

2. In a machine of the class described, the combination with a casing of a screen drum, blades rotatably mounted within and to cooperate with the drum, a support on which the blades are mounted, means for rotating the blade support, said blades being arranged in pairs, each pair consisting of a preceding pulp-impelled blade and a succeeding pulp-impelling blade, the pulp-impelled blade being inclined to impart a blade-rotating movement to the blade support under the feeding pressure of the pulp, the pulp-impelling blade being also inclined with an increasing pitch toward its outer edge, thereby to afford both a wide distributing surface and an accelerated discharge for the pulp, means for feeding pulp from within and radially outward between the blades, said pulp being fed between a pulp-impelled blade and the next succeeding pulp-impelling blade only.

3. In a machine of the class described, the combination with a screen drum, impeller blades mounted within the drum for rotation relatively to the screen, said blades be-

ing arranged in pairs, said blades being arranged to provide intermediate spaces, and means for feeding pulp between the blades at alternate spaces only.

4. In a machine of the class described, the combination with a hollow screen of impeller blades within the screen and means for rotating said blades, certain of said blades being pulp-impelled blades inclined radially backward from the direction of rotation to transform the impact of the pulp into rotative movement, and means for feeding the pulp to the back of the pulp-impelled blades only.

5. In a machine of the class described, the combination with a casing of a hollow screen, blades rotatably mounted within and coöperating with the screen, said blades including pulp-impelled blades and pulp-impelling blades, the former being inclined to transform the pressure of the pulp into blade rotative movement and the latter being inclined radially backward to provide a wide distributing surface with an increasing pitch toward its outer edge, thereby to give an accelerated discharge to the pulp, and means for feeding pulp to the back of said pulp-impelled blades and the front of said pulp-impelling blades only.

6. In a machine of the class described, the combination with a casing of a hollow screen and blades rotatably mounted within and to coöperate with the screen, said blades including pulp-impelling blades inclined radially backward with relation to the direction of rotation and formed to give an accelerated discharge to the pulp, and means for discharging pulp from within and radially outward upon said blades.

7. In a machine of the class described, the combination with a screen of impeller means including a pulp-impelling blade having a cross section providing for a pulp-receiving surface extending in an approximately radial direction succeeded in the radial direction by a distributing surface inclined rearwardly with reference to the pulp-receiving surface and terminating in a discharge surface again approximating a radial direction to give an accelerated discharge to the pulp.

8. In a machine of the class described, the combination with a casing of a screen, impeller means rotatable within the screen and including a pulp-impelled blade and a succeeding pulp-impelling blade, and means for feeding pulp to the back of the former and the front of the latter only.

9. In a machine of the class described, the combination with a casing of a screen drum, impeller means rotatably mounted within and to coöperate with the drum, and a pulp inlet communicating with the interior of the drum and within the impeller means, an outlet for the screened stock communicating with the exterior of the drum, a waste out-

- let also communicating with the interior of the drum, and means for utilizing the feeding pressure upon the pulp for driving the impeller means.
- 5 10. In a machine of the class described, the combination with a casing of a screen, blades rotatably mounted within and to co-operate with the screen and means for feeding pulp to the front face of each alternate 70
10 blade only.
11. In a machine of the class described, the combination with a casing of a screen, blades rotatably mounted within and to co-operate with the screen, and means for feeding pulp to the front faces of certain blades only while withholding it from the faces of intermediate blades.
12. In a machine of the class described, the combination with a screen of impeller 75
20 means co-operating therewith comprising a plurality of impeller blades, means for feeding pulp to the interior of the screen, and means to impart to each portion of the stock so fed a plurality of blade impacts.
- 25 13. In a machine of the class described, the combination with a casing of a screen, means for feeding pulp intermittently to any given area of the screen, and means for imparting to said pulp a plurality of blade impacts prior to the feeding of additional stock to the same area.
14. The method of screening pulp which consists in feeding a portion of pulp to a screening area and imparting a plurality of 80
35 beats to it while undergoing screening prior to the feeding of further pulp to the same area.
15. In a machine of the class described, the combination with a casing of a screen 85
40 drum, blades rotatably mounted within and to co-operate with the drum, means for rotating the blades, said blades being arranged in pairs, means for feeding pulp from within and radially downward between the 90
45 blades comprising one or more internally arranged pulp discharge orifices, and means to direct the pulp from said orifice or orifices between certain blades only and preventing its discharge between intermediate blades.
- 50 16. In a machine of the class described, the combination with a screen of impeller means within the screen comprising a plurality of blades of alternately varying section.
- 55 17. In a machine of the class described, the combination with a screen of impeller means within the screen comprising a plurality of blades of similar length and height but alternately varying inclination.
- 60 18. The combination with a screen of impeller means within the screen, said impeller means having a plurality of blades, said blades being of similar length and height but of varying radial inclination.
- 65 19. In a machine of the class described, the combination with a screen of impeller means within the screen comprising blades arranged in pairs, each pair being formed in one unit and comprising two differently shaped blades. 70
20. As a new article of manufacture a pair of impeller blades for a pulp screen formed as a unit, said blades being of similar shape in projection.
21. As a new article of manufacture, a 75
blade unit for a pulp screen comprising a pair of blades formed integral with a single blade support and adapted to be fastened to a rotative member.
22. As a new article of manufacture a 80
blade unit for a pulp screen comprising a pair of impeller blades, a common support at one end by which they are to be attached to a rotative member and a connecting rib near the opposite end. 85
23. As a new article of manufacture, an impeller wheel for a pulp screen having impeller blades and water conducting members extending longitudinally of said blades and terminating at different longitudinal locations. 90
24. As a new article of manufacture, an impeller wheel for a pulp screen having impeller blades and water conducting plates formed integrally with the blades and extending longitudinally of said blades and terminating at different longitudinal locations. 95
25. In a machine of the class described, the combination with a casing of a screen, impeller blades rotatably mounted within and to co-operate with the screen, a circumferentially arranged pulp supply orifice within the drum and blades to discharge stock outwardly between the blades and 100
105 means for preventing the discharge of stock between certain of the impeller blades.
26. In a machine of the class described, the combination with a casing of a screen, impeller blades rotatably mounted within 110
115 and to co-operate with the screen, a circumferentially arranged pulp supply orifice within the drum and blades to discharge stock outwardly between the blades and means for preventing the discharge of stock between certain of the impeller blades, said means comprising obstruction members carried between the blades and tending to cut off communication between the said orifice and the intermediate space between said 120
125 blades.
27. In a machine of the class described, the combination with a casing of a screen, blades rotatably mounted within and to co-operate with the screen, means to feed pulp from within and outward between the blades, said means comprising an annular discharge orifice for feeding the pulp from the end of the screen-inclosed space to the interior thereof, and means to direct pulp 130

from said orifice between certain blades only, preventing its discharge between intermediate blades comprising obstruction members carried by the blades and closing communication from the said orifice to the spaces between intermediate blades.

28. In a machine of the class described, the combination with a casing of a hollow, horizontal screen, impeller blades rotatably mounted within and to coöperate with the screen, means for rotating the blades, means for feeding the pulp from within and outward between the blades, said blades being inclined longitudinally to feed the unscreened stock toward one end of the screen, said feeding means comprising a plurality of feeding passages terminating in feeding orifices arranged at different points lengthwise the blades, and means dependent on variations in the rate of pulp supply for controlling the distribution of pulp to said passages.

29. In a machine of the class described, the combination with a casing of a hollow, horizontal screen, impeller blades rotatably mounted within and to coöperate with the screen, means for rotating the blades, means for feeding the pulp from within and outward between the blades, said blades being inclined longitudinally to feed the unscreened stock toward one end of the screen, said feeding means comprising a plurality of feeding passages terminating in feeding orifices arranged at different points lengthwise the blades, and means dependent on variations in the rate of pulp supply for controlling the distribution of pulp to said passages.

30. In a machine of the class described, the combination with a horizontal screen of impeller means within the screen, means to direct stock upon said impeller means at a plurality of differently positioned points lengthwise the screen, the unscreened stock being traversed lengthwise the screen to a waste discharge outlet, and means for automatically distributing the stock to said different points dependent on the variations in the rate of pulp supply.

31. In a machine of the class described, the combination with a horizontal screen of impeller means within the screen, means to direct stock upon said impeller means at a plurality of differently positioned points lengthwise the screen, the unscreened stock being traversed lengthwise the screen to a waste discharge outlet, and means for directing the pulp at will to any of said differently located points of application lengthwise the screen.

32. In a pulp screen the combination with a screen drum, impeller means within the drum, a plurality of differently positioned pulp supply orifices, separate passages connecting said orifices and an overflow plate

separating one passage from another and permitting only an excess of pulp supply to enter said first-named passage.

33. In a pulp screen the combination with a screen drum, propeller means, a plurality of pulp supply passages and an adjustable weir plate for controlling said passages.

34. In a machine of the class described, the combination with a screen and impeller means to apply the pulp to the screen, means for feeding the pulp to said impeller means from a variable source of supply, and means to distribute the pulp to said impeller means dependent on variations in the rate of supply.

35. In a machine of the class described, the combination with screening means of means automatically to regulate the extent of screening with reference to variations in the rate of supply.

36. In a machine of the class described, the combination with a screen of impeller blades within the screen, means for feeding pulp from within and outward between the blades, said means comprising an annular feeding passage terminating in an annular orifice and a second annular feeding passage within the first and terminating in an annular orifice differentially located with reference to the first orifice.

37. In a machine of the class described, the combination with a screen of impeller blades within the screen, means for feeding pulp from within and outward between the blades, said means comprising an annular feeding passage terminating in an annular orifice and a second annular feeding passage within the first and terminating in an annular orifice differentially located with reference to the first orifice, and means for distributing pulp to said passages dependent on the variations in the source of supply.

38. In a machine of the class described, the combination with a screen of impeller blades within the screen, means for feeding pulp from within and outward between the blades, said means comprising an annular feeding passage terminating in an annular orifice, and a second annular feeding passage within the first and terminating in an annular orifice differentially located with reference to the first orifice, and means for feeding pulp to said first-named passage and an excess of supply to said last-named passage.

39. In paper manufacture the combination with a centrifugal screen of a liquid feeding device within the interior thereof comprising a rotatable housing and a stationary water supply, means for delivering water to said housing, the latter being cone-shaped in form and having discharge orifices located near the largest diameter of the cone.

40. In paper manufacture the combina-

tion with a centrifugal screen of a liquid feeding device within the interior thereof comprising a rotatable housing and a stationary water supply, means for delivering 5 water to said housing, the latter having a discharge portion of maximum diameter provided with discharge orifices.

41. In a pulp screen the combination with a screen drum, a plurality of impeller blades 10 within the drum, means for feeding pulp to the blades, and means for feeding water between one pair of blades to one point lengthwise the screen and between another pair of blades to a different point lengthwise the 15 screen.

42. In a pulp screen the combination with a screen drum, a plurality of impeller blades within the drum, means for feeding pulp to the blades, means for feeding water from 20 within between the blades, and deflecting means of different longitudinal extent between the blades for applying the water to the screen at different points lengthwise the blades.

43. In a pulp screen the combination with a screen drum of impelling blades within the drum, means for rotating said blades, means for discharging shower water radially outward between the blades and curved 30 deflecting plates to receive the water between the blades, said plates being of different longitudinal extent to direct the water from the screen upon the pulp being screened at different points lengthwise the screen.

44. In a machine of the class described, the combination with a screen, blades rotatably mounted within and to coöperate with the screen, means for rotating said blades, the latter being arranged in pairs, means for 40 feeding pulp between one pair of blades and means for feeding shower water between the next adjacent pair of blades.

45. In a machine of the class described, the combination with a casing of a screen 45 drum, blades rotatably mounted within and to coöperate with the drum, means for feeding pulp between the blades and a water distributing member carried and rotatable with the blades, said member having one or more 50 circumferential orifices for centrifugally discharging water between the blades.

46. In a machine of the class described, the combination with a casing of a screen drum, blades rotatably mounted within and 55 to coöperate with the drum, means for feeding pulp between the blades and a water distributing member carried and rotatable with the blades, said member having a plurality of discharge orifices for discharging the 60 water centrifugally to the blades, said orifices registering with the spaces between certain blades only.

47. In a pulp screen the combination with a rotatable screen drum of impeller blades 65 rotatably mounted within the drum, means

for feeding pulp to the blades to be forced against the interior of the screen and means to control the rotation of the screen caused by the forcing of the pulp against the same.

48. In a pulp screen the combination with 70 a rotatable screen drum of impeller blades rotatably mounted within the drum, means for feeding pulp to the blades to be forced against the interior of the screen and means to control the rotation of the screen caused 75 by the forcing of the pulp against the same, said means comprising an adjustable braking member.

49. In a pulp screen the combination with 80 a rotatable screen drum, a shaft geared to said drum, a braking drum on said shaft, a brake for said drum, means to adjust said brake, impeller means within the screen, means for rotating said impeller means, and means for feeding pulp to said impeller 85 means.

50. In a pulp screen the combination with a casing, a rotatable screen drum, impeller blades within the drum, means for rotating said impeller blades, means for feeding pulp 90 to said impeller blades, and means providing for the automatically controlled rotation of the drum.

51. In a machine of the class described, the combination with a casing of a screen 95 drum, blades rotatably mounted within and to coöperate with the drum, a support on which the blades are mounted, means for rotating the blade support, said blades being arranged in pairs, each pair consisting of 100 a preceding pulp-impelled blade and a succeeding pulp-impelling blade, the pulp-impelled blade being inclined to impart a blade-rotating movement to the blade support under the feeding pressure of the pulp, the pulp-impelling blade being also inclined with an increasing pitch toward its outer edge, thereby to afford both a wide distributing surface and an accelerated discharge for the pulp, means for feeding pulp 105 from within and radially outward between the blades, said pulp being fed between a pulp-impelled blade and the next succeeding pulp-impelling blade only, said feeding means comprising oppositely disposed sets 110 of annular feed spouts for feeding the pulp from the ends of the drum to the interior of the drum - inclosed space and radially outward from between the blades, each set having a plurality of annular discharge orifices disposed at different positions lengthwise the blades, feeding passages leading from a common source of supply to said discharge orifices, and means to distribute the stock to the several orifices comprising 115 a dam or gate to direct the stock to one orifice but permit the overflow to another, said gate being movable to exclude the stock from one orifice, means to direct the stock from said orifices or orifice between alter-

- 5 nate pairs of blades or to certain blades only, preventing its discharge between intermediate blades thereby to provide for an intermittent feeding of the stock from the outlets to the screen drum and for a plurality of impacts by the blades against each portion of stock so fed, such means consisting of obstruction members carried by the blades and obstructing the free passage of
- 10 5 the pulp from the annular outlets to the spaces between intermediate blades or alternate sets of blades, thereby to provide pulp-receiving pockets between the blades and other intermediate non-pulp-receiving
- 15 10 pockets.
52. In a machine of the class described, the combination with a casing, a screen drum, blades rotatably mounted within and to coöperate within the drum, means for
- 20 20 rotating said blades, means for forcing pulp from within and radially outward between certain pairs of the blades, means for supplying water to the spaces between the pulp-receiving blades or to the non-pulp-receiving
- 25 25 spaces and for distributing the same to a plurality of points lengthwise the blades and the screen drum, said means including a rotatable water distributing chamber carried by and rotatable with the blades, means
- 30 30 for supplying water to said chamber comprising a fixed supply conduit discharging into said chamber through an open end and means for discharging the water centrifugally from said receptacle, the latter for
- 35 35 that purpose having a central enlargement provided with one or more discharge orifices annular in form in operative relation to the open spaces between the blades, and means for conveying the water discharged
- 40 40 through said orifice between the blades to different longitudinal distances comprising longitudinally extending baffle plates of different length.
53. In a machine of the class described,
- 45 45 the combination with a casing of a screen drum, blades rotatably mounted within and to coöperate with the drum, a support on which the blades are mounted, means for rotating the blade support, said blades being
- 50 50 arranged in pairs, each pair consisting of a preceding pulp-impelled blade and a succeeding pulp-impelling blade, the pulp-impelled blade being inclined to impart a blade-rotating movement to the blade support under the feeding pressure of the pulp, the pulp-impelling blade being also inclined with an increasing pitch toward its outer edge, thereby affording both a wide distributing surface and an accelerated discharge for
- 55 55 the pulp, means for feeding pulp from with-
- in and radially outward between the blades, said pulp being fed between a pulp-impelled blade and the next succeeding pulp-impelling blade only, said feeding means comprising oppositely disposed feed spouts having annular outlet orifices for feeding the pulp from the ends of the drum to the interior of the drum-inclosed space and radially outward from between the blades, means to direct the stock from said orifices between alternate pairs of blades or to certain blades only, preventing its discharge between intermediate blades thereby to provide for an intermittent feeding of the stock from the outlets to the screen drum and for a plurality 75 of impacts by the blades against each portion of stock so fed, such means consisting of obstruction members carried by the blades and obstructing the free passage of the pulp from the annular outlets to the spaces between intermediate blades or alternate sets of blades, thereby to provide pulp-receiving pockets between the blades and intermediate non-pulp-receiving pockets.
54. The method of screening pulp which 80 consists in feeding a portion of pulp to a screening area, beating the same and thereafter applying shower water to the un-screened pulp.
55. In paper manufacture the combination with a centrifugal screen of a liquid feeding device within the interior thereof comprising a rotatable housing and a stationary water supply, said housing having discharge orifices arranged in its periphery.
56. In a pulp screen the combination with a rotatable screen drum of impeller blades rotatably mounted within the drum, said drum being rotatable under the influence of pressure from within the same, and means 100 to control the rotation of the drum.
57. An impeller for use with pulp screens comprising a wheel having impeller blades radially distant from the axis thereof, a water-receiving chamber inwardly of the 105 blades said chamber having outlets opening to immediately succeeding spaces between the blades.
58. A process of screening pulp consisting of alternately delivering a batch of pulp to the screening means and discharging water on the delivered batch.
- In testimony whereof, I have signed my name to this specification, in the presence of two subscribing witnesses.
